(57) **CLAIM**

The ornamental design for a bag packaging, as shown and described.

DESCRIPTION

The patent or application file contains at least one drawing executed in color. Copies of this patent or patent application publication with color drawing(s) will be provided by the Office upon request and payment of the necessary fee.

1. Bag packaging

1.1 : Perspective

1.2 : Front

1.3 : Back

1.4 : Left

1.5 : Right

1.6 : Top

1.7 : Bottom

The parts shown by means of broken lines in the reproductions are not part of the claimed design. The long-dashed lines appearing in the front view, the rear view, the top view, and the perspective view are perforations for opening, forming part of the claimed design.

1 Claim, 7 Drawing Sheets
